UNITED STATES PATENT OFFICE.

SAMUEL MICHAEL JENKS, OF MADISON, SOUTH DAKOTA.

OVERHEAD CARRIER.

SPECIFICATION forming part of Letters Patent No. 673,270, dated April 30, 1901.

Application filed January 14, 1901. Serial No. 43,239. (No model.)

To all whom it may concern:

Be it known that I, SAMUEL MICHAEL JENKS, a citizen of the United States, and a resident of Madison, in the county of Lake and State 5 of South Dakota, have invented a new and Improved Overhead Carrier, of which the following is a full, clear, and exact description.

This invention relates to an overhead carrier adapted especially for carrying hay and 10 analogous loads from one place to another—for example, from a wagon into a barn for storage.

The carrier is adapted to be used with a 15 sling, which may be of any desired construction, but which is preferably of that construction described and claimed in my copending application for patent on slings for overhead carriers, filed January 29, 1901, Serial No. 45,190.

20 This specification is a specific description of one form of the invention, while the claims are definitions of the actual scope thereof.

Reference is to be had to the accompanying drawings, forming a part of this specification, 25 in which similar characters of reference indicate corresponding parts in all the views.

Figure 1 is an end elevation of the carrier with the track in section on the line 1 1 of Fig. 3. Fig. 2 is a side view of the carrier. 30 Fig. 3 is a longitudinal section thereof, showing the latch of the carrier locked with the sling; and Fig. 4 is a section showing the latch in unlocked position.

a represents the track on which the carrier 35 runs. This track is suspended by hangers a' and is provided at a certain predetermined point with a downwardly-projected stud or pin a², the latter for coaction with the carrier, as will be hereinafter explained. The detailed 40 construction of the track is set forth in my copending application for patent on overhead tracks, filed January 14, 1901, Serial No. 43,240. The carrier comprises two side frames b, which are fastened rigidly together by tie-bolts or the like b' and which have secured 45 between their lower portions a casing c, having a bell or funnel shaped skirt c' at its lower end, this skirt projecting below the side frames b and having an open lower end. 50 Wheels b² are carried by the side frames b and run on the track a, as shown. By these means the carrier is mounted to move freely

along the track, the side frames b straddling the track, as shown. Within the casing c a latch d is mounted to rock upon a pin d', fixedly carried in the casing. The latch d comprises a hook d², an arm d³, adjacent to the hook, and an arc-shaped track d⁴, terminating at one end in a cavity d⁵ and at the other end in a shoulder d⁶. The parts are so arranged that the latch d will normally hang in the position shown in Fig. 4, which position is taken owing to the preponderating force of gravity attending the arm d³. In Figs. 3 and 4, e represents an eye forming part of the sling which works with the carrier. Assuming that the parts are in the position shown in Fig. 4, the eye e, moving upward, will engage the arm d³ and throw the latch into the position shown in Fig. 3, in which position the hook d² is engaged in the eye e.

Acting with the latch d is a lock f, mounted in the upper part of the casing c and arranged to rock upon a pin f', fixed in the casing c. This lock f comprises two arms f² and f³, the latter having a hook-shaped end and the two arms being spaced apart a distance approximately equal to the length of the detent or stud a² on the track. The lock f is also provided with a roller f⁴, located at its lower portion and adapted to run on the track d⁴ of the latch d. The shoulder d⁶ of the latch strikes the roller f⁴ and limits the movement of the latch toward the open position, (see Fig. 4,) and when the latch moves oppositely 85 its movement is checked at the proper time and the latch is held securely in closed position by the engagement of the roller f⁴ with in the depression or cavity d⁵ in the latch. (See Fig. 3.) Therefore when the latch moves 90 from the position shown in Fig. 4 to that shown in Fig. 3 the track d⁴ runs along the roller f⁴ and the lock drops into the position shown in Fig. 3, whereupon the movement of the latch d will be finished. When in this 95 adjustment, the lock f serves to prevent the return of the latch to the open position. (Shown in Fig. 4.)

Assuming now that the parts are in the adjustment shown in Fig. 3 and that the carrier is moving in the direction of the arrow indicated at g in Fig. 3, the hooked end of the arm f³ of the lock will engage with the detent a² and the lock will thereby be thrown

to the position shown in Fig. 4. This movement of the lock releases the latch and permits the sling, of which the eye *e* forms a part, to drop from the carrier. The above-described movement of the lock results, further, in the upward movement of the arm *f*² thereof, causing this arm to act with the arm *f*³, the two embracing the detent *a*² and securely locking the carrier therewith, preventing the carrier from moving farther on the track until the parts are moved from the position referred to. The carrier is thus stopped and held stationary during the descent of the sling to discharge or receive its load, as the case may be. The lock returns to the position shown in Fig. 3, when the latch is returned to its closed or inactive position.

The carrier is provided with sheaves *h*, mounted on transverse pins *h'* and arranged, respectively, at its sides, the sheaves serving to carry the ropes for operating the sling and also for hauling the carrier, and these sheaves *h* coact with the sheaves *i*, also mounted on the carrier, the sheaves *i* serving to guide the rope in its movement. The arrangement of this rope has nothing to do with the organism forming the subject-matter of this case; but a complete disclosure of the point involved is embodied in the above-referred-to copending application for slings for overhead carriers.

Having thus described my invention, I claim as new and desire to secure by Letters Patent—

1. An overhead carrier having a pivotally-mounted latch provided with a hook and an arm juxtaposed to each other for the purpose specified, the latch also having an arc-shaped track terminating at one end in a depression

and at the other end in a stop, and a lock for 40 the latch, the lock having a part engaging the track and adapted to enter the depression to lock the latch and to engage the stop to limit the opening movement of the same.

2. A carrier, comprising a casing, a latch 45 pivoted in the casing, said latch being provided with a hook, an arm and an arc-shaped track terminating at one end in a shoulder and at the other end in a depression, and a pivoted lock above the latch, said lock being 50 provided with two arms, one having a hook-shaped end, and with a roller adapted to run on the track, substantially as described.

3. The combination of a track, a stud carried thereby and projecting therefrom, a carrier running on the track, a latch pivotally mounted in the carrier and comprising a hook and an arm juxtaposed to each other and also comprising an arc-shaped track with a cavity or depression at one end, and a shoulder 60 at the other end and a lock having a part engaged with the track on the latch and capable of entering the depression in the latch, to hold the latch in closed position and to engage the shoulder to limit the opening movement of the latch, the lock having two juxtaposed arms capable of straddling the detent 65 on the track to hold the carrier stationary, the detent lying in the path of the arms on the lock.

In testimony whereof I have signed my name to this specification in the presence of two subscribing witnesses.

SAMUEL MICHAEL JENKS.
